Sewing machines of the type having an opening or aperture in the base plate adjacent the stitch plate to provide access to the looper or other stitch forming means below the base plate, are provided (1) with a slider or closure for such aperture, the slider being curvable or bendable about an axis running transversely to the direction of movement of the slider, and (2) with a passageway which guides the end of the slider downwardly within the edges of the base plate when moved to open the aperture.

SLIDE FOR PROTECTION OF AN OPENING IN THE BASE PLATE OF A SEWING MACHINE

The invention concerns a sewing machine with a slide which protects or walls off an opening in the base plate of the sewing machine which is provided to cover the area over the stitch forming device.

Generally, these apertures in the base plate are covered by a rigid slide which is accommodated in guide grooves of the base plate. By aligning the upper surface of such a slider with the goods contacting surface or upper surface of the base plate, while a thin edge of the slider is surrounded by the base plate edges. For opening or exposing the aperture, the slider will be pushed from its covering position so that a part of the slider projects away from the edge of the base plate. A slider of this kind is especially disadvantageous when the sewing goods support surface of the base plate has been aligned with the table top of a supporting table. In this case, the slider can be pushed to open position only when the sewing machine is lifted or pivoted upwardly beforehand. Besides, there exists the danger that, through carelessness, the sewing machine will drop, while the slider is still in open position, and thereby injure the table top and bend the slider.

A further important drawback of the conventional slider relates to the fact that different sized openings in the base plate necessitate many different sizes of sliders. There is such a necessity, for example, with two-needle sewing machines where the breadth of the stitch plate for different needle spacing and therefore the size of the opening to be covered in the base plate changes.

This invention is based on the problem of providing a protecting cover for the opening in the base plate of sewing machine which in the closed and in the open positions remains within the edges of the base plate surrounded in the vertical reaches of the base plate and which is so constructed that one size of slider or protecting cover serves to cover the openings when various sizes of stitch plates are employed.

The solution of this problem comprises the employment of a slider covering means which is deformable laterally to the shifting direction about a bending axis and which is downwardly divertable through a guide means in the area of the base plate edge.

Through the structure of the invention, a slider is provided, which is moved out into its open position by sliding the same back and downwards, within the reaches of the base plate and not just laterally on the base plate. On this basis, such a slider can also be moved to open position while the sewing machine is supported at table top level on a supporting structure.

With different size openings in the base plate, the slider of the invention will be shifted more or less further in the direction of the stitch plate for the protection of the opening, whereby the part of the slider not required for the covering of the actual opening is placed in its downwardly curved position. Similar and like-sized sliders of the invention can be employed for one-needle sewing machines and for two-needle sewing machines with different sized needle spacing. This results in a reduction in the cost of manufacture and simplifies storage of the sliders.

Where, generally, only a slight spacing is available between the looper device of a sewing machine and the

covering slider, care must be taken as to such details, that the slider of the invention must not be allowed to be pressed down onto the looper. Accordingly, the invention further proposes to couple the slider at the end 5 adjacent the stitch plate with a bend resistant plate. This plate, by way of example, can be made of the known rigid steel plate covering material, and covers the looper at the front part of the slide to thereby prevent sagging of this part of the cover upon the occurrence of a relatively large downwardly directed force 10 which sagging would prevent the rotary motion of the looper and the stitch forming operation.

Further details of the invention are given in the following description of specific examples shown in the 15 drawing. In the drawing:

FIG. 1 is a plan view of a base plate of a sewing machine equipped with a slider made according to the invention.

FIG. 2 is a transverse section of the slider of the invention taken on lines II — II of FIG. 1.

FIG. 3 is a transverse sectional view, with one part cut away, taken on line III — III of FIG. 1 showing the slider of the invention.

FIG. 4 is a greatly enlarged detail view of an end portion of a slider made according to the invention.

In the table plate 1 of the sewing machine chassis, the base plate 2 of a two-needle machine is fixed, wherein for the sake of clarity, the supports and casing bracket are not shown. The sewing goods contact surface 3 of 30 base plate 2 lies in the plane of the upper side of the table plate 1. In the base plate 2, there is positioned a stitch plate 4 for a proportionally predetermined broad needle spacing by which the stitch holes 5 are separated correspondingly from one another. According to FIG. 1, there is arranged to the right of the stitch plate 4, a rigid slider 6 which covers the right looper (not shown) of the sewing machine. The slider 6, with its upper side within the plane of the contact surface 3 of base plate 2 for the sewing goods, can be pushed horizontally to an open position, there being provided in the base plate 2 a recessed surface 7 adapted to receive the lower surface of slider 6.

The slider 8 of the invention serves as a cover for the left looper 9, which are sketched in FIG. 2 in dot-dash lines, or for the closure of the opening 11 of the base plate 2 extending between the left edge of stitch plate 4 (FIGS. 1 and 2) and the shouldered thickening 10 (FIG. 2) of the base plate 2.

The slider 8 comprises a unit-to-unit resilient, tear-resistant, synthetic material, polyamide for example, manufactured plate, which on its underside has a plurality of grooves 12 extending laterally of the slide direction, V. At the ends of the ribs 13 which extend between lateral grooves 12, laterally extending short guiding ears 14 are formed.

The slider 8 is made by injection molding techniques, suitable arrangements can be made to have the slider 8 united with the plate 15 simultaneously with the molding of the slider 8.

By way of a specific example, the plate 15 is formed with a cleft 17 therein and the cleft is provided with a plurality of holes 18 (see FIG. 4). Such a plate 15 is inserted in the mold in such a way that during molding, the holes and the cleft are filled in so that the slider 8 is firmly bonded to the plate 15.

In the base plate 2, a surface depression 19 is provided passing along the sides of the opening 11, extend-

ing parallel to the sewing goods supporting surface to about the middle of the shoulder 10 and proceeding from there to curve downwardly.

Inserted in the depression 19 is a U-form frame having two legs 21 extending horizontally along the area of the shoulder 10, the legs being connected by a guide strip 22, and with the upper side of said frame lying in the plane of the sewing goods surface 3. The guide strip 22 reaches up to the edge 23 of the base plate 2 and has an underside adapted to follow the curved part of depression 19.

On the underside of the legs 21 facing, along-side the longitudinal direction of the opening 11, there is provided a longitudinal recess 24 (FIG. 3) which continues on the underside of curved guide strip 22 to provide continuous recesses 24.

In the guide strip 22, a further recess 25 is provided which lies symmetrical with recess 24, is likewise curved and is about twice as deep as recess 24. The depression 19 and the frame 20, accordingly form two straight guide grooves 26, in the area of legs 21 and also form, in the area of guide strip 22, a curved, shaded-off guide groove 27 in which are arranged, respectively, the guide lugs 14 of slider 8 and the guide lugs 16 of plate 15.

By shifting in the slide direction V, the entering part of slider 8 will be steered either into the curved guide groove 27 or the horizontal position, the lateral grooves 12 thereof facilitating the deflecting or curving operation.

The downwardly deflected part of slider 8 remains enclosed within the edge 23 of the base plate along a vertical plane in the vertical region of the base plate wherefore the slider 8 also can be pushed to the open position when a sewing machine is mounted on a support with its sewing surface aligned in the plane of the upper surface of the support.

When using a narrow stitch plate, the slider can be

pushed still further to the right, as shown in the drawing, without having its end slid out of the guideway 27. For this object, the legs 21 of frame 20 are constructed so that they reach to the left edge of the narrowest stitch plate.

The width of plate 15 corresponds essentially to the diameter of the loopers 9 so that it is guaranteed that the part above the looper of the cover of the invention has great strength so as not to sag down to contact the looper.

Where the slider 8 consists of resilient material, and accordingly to prevent buckling is given certain strength, the effort is made to closely fit the slider within the arched recesses 24,25. Fundamentally, the depression 19 in the region of the connecting part 22 is not required to be curved as shown. It suffices when the shouldered portion is beveled at the edge with the corners rounded off.

I claim:

1. In a sewing machine of the type having a base plate, a stitch plate in the base plate, and an aperture in said back base plate adjacent the stitch plate and above a stitch forming device, the improvement comprising a slider comprising a resilient portion for covering said aperture, guide means in the base plate for guiding said slider back and forth in one direction, said guide means comprising a downwardly diverted portion in that area of said aperture nearest the edge of the base plate, the resilient portion of said slider comprising a plate which is provided on its under side with a series of grooves directed transversely with respect to the direction of movement of the slider whereby said slider is adapted to follow the diverted portion of said guide means.
2. A sewing machine as claimed in claim 1 wherein said slider has an attached bend resistant portion at the end nearest the stitch plate of the machine.
